STRING OF DECORATIVE LIGHTS

Fulvio Bossi, Milan, Italy, assignor to Frankel Associates, Inc., New York, N. Y.

Application March 27, 1956, Serial No. 40,801

Term of patent 14 years

(Cl. D29—1)

Fig. 1 is a front perspective view of a string of decorative lights, showing my new design, and

Fig. 2 is an edge view thereof.

The bulbs and reflectors are integral and are permanently secured in the chain.

The design unit is contained between the dot and dash lines, which unit is repeated in regular succession as indicated by the extensions beyond the unit boundaries.

The dominant feature of my design, resides in the portions shown in solid lines.

I claim:

The ornamental design for a string of decorative lights, substantially as shown and described.
